UNITED STATES PATENT OFFICE.

GEORGE D. POGUE, OF ST. LOUIS, MISSOURI.

METHOD AND APPARATUS FOR LUBRICATING MACHINE-CYLINDERS.

1,205,662.

Specification of Letters Patent. Patented Nov. 21, 1916.

Application filed May 19, 1915. Serial No. 29,169.

To all whom it may concern:

Be it known that I, GEORGE D. POGUE, a citizen of the United States, residing at St. Louis, Missouri, have invented a certain

5 new and useful Improvement in Methods and Apparatus for Lubricating Machine-Cylinders, of which the following is a full, clear, and exact description, such as will enable others skilled in the art to which it applies

10 to make and use the same.

This invention relates to machines of the type that comprises a cylinder and a piston for compressing a fluid that is admitted to the cylinder.

15 While my invention is particularly applicable to internal combustion engines of the Diesel type, or similar types, in which liquid fuel is introduced directly into air in the cylinder that is under high compression, and

20 while I have herein illustrated my invention applied to a machine of the type just mentioned, I wish it to be understood that the invention is not limited to internal combustion engines, as it is applicable to various

25 other kinds of machines in which a piston is employed for compressing air or other fluid that is either sucked into the cylinder or forced into the cylinder under pressure.

One object of my invention is to provide 30 a novel method of lubricating the coöperating surfaces of a cylinder and the piston that is reciprocatingly mounted in the cylinder.

Another object is to provide a novel 35 method of lubricating the internal walls of the cylinder of an internal combustion engine of the type in which the air that supports combustion is taken into the cylinder without first passing through a carbureting device.

Another object is to provide an efficient apparatus for practising my method.

Another object is to provide an internal combustion engine which comprises means 45 for causing a dry lubricant in a pulverized, flaked or finely divided state to be admitted to the cylinder of the engine so as to lubricate the coöperating surfaces on the cylinder and piston and prevent the piston rings from sticking.

Another object is to provide an internal combustion engine of the type just mentioned, which is so designed that the quantity of lubricant that is admitted to the cylinder and the frequency of admission can be accurately controlled.

Other objects and desirable features of my invention will be hereinafter pointed out.

Figure 1 of the drawings is a vertical sectional view, illustrating a portion of a four-cycle internal combustion engine of the Diesel type constructed in accordance with my invention. Fig. 2 is a horizontal sectional view of the mechanism employed in said engine for actuating the member that governs the admission of the lubricant to the current of air that conveys the lubricant into the cylinder of the engine. Fig. 3 is a detail vertical sectional view taken on the line 3—3 of Fig. 2. Fig. 4 is a top plan view 70 of the engine shown in Fig. 1; and Fig. 5 is a top plan view of a two-cycle internal combustion engine.

My method, briefly described, consists in conveying a dry lubricant in finely divided 75 form into the cylinder of an engine or machine by means of air that is admitted to the cylinder, thereby causing the coöperating surfaces on the cylinder and piston to be adequately lubricated, and eliminating 80 the possibility of the piston rings sticking on account of not being properly lubricated.

The apparatus that I prefer to use for practising my method consists of a means 85 operated either mechanically or manually for introducing or admitting a dry, finely divided lubricant into a current of air or other fluid that is traveling into the cylinder of the machine. In the machine herein shown, which consists of an internal combustion engine, the means that governs the admission of the lubricant to the current of air that is traveling to the cylinder is operated automatically, preferably at regular intervals, said means being so designed that the 90 lubricant will be supplied to the cylinder in relatively small quantities. The air that is admitted to the cylinder to support combustion is utilized to convey the lubricant into the cylinder, and the mechanism that governs the operation of the means that admits or introduces the lubricant into the inflowing air is preferably operated by some moving part of the engine.

Referring to Figs. 1 to 3 of the drawings 105 which illustrate a four-cycle internal combustion engine of the Diesel type constructed in accordance with my invention, A designates one of the cylinders of the engine and B the piston that operates in said 110 cylinder, the cylinder A being provided with an intake 1 through which air is

drawn into the cylinder on the suction stroke of the piston and also provided with a discharge pipe 2 through which the burnt gases escape from the cylinder. A receptacle C that contains a dry lubricant in pulverized, flaked or finely divided form, such for example, as graphite or plumbago, is combined with a controlling device D, which, at certain intervals, causes a measured or definite quantity of the dry lubricant in the container C to be introduced into the cylinder A. In the form of my invention herein shown the device D governs the admission of the dry lubricant to all of the cylinders of the engine, but it will, of course, be obvious that individual lubricant-controlling devices could be employed for each cylinder, if desired. The device D consists of a solid cylindrical-shaped member that is rotatably mounted in a horizontally-disposed housing 3 at the lower end of the receptacle C which is of hopper form, said device D normally acting as a closure for the discharge opening at the lower end of the hopper C. The device D is provided with a plurality of openings 4, one for each cylinder, that extend transversely through same, as shown in Fig. 1, which openings are filled automatically with the dry lubricant in the hopper C when the device D is in its filling position, namely, in such a position that the openings 4 therein will be positioned vertically and in alignment with the discharge opening at the lower end of the hopper C. When the device D is moved into the position shown in Fig. 1, which I will term its discharge position, the openings 4 therein align with air pipes 5 and 5^a that constitute air conduits or passageways which lead to the cylinders of the engine, the pipes 5 being connected with the air intake pipes 1 of the cylinders and terminating at their opposite ends at the interior of the housing 3 in which the device D is rotatably mounted, and the pipes 5^a being open to the atmosphere and having their opposite ends terminating at the interior of said housing 3. It will thus be seen that the device D acts as a cut-off valve for the air conduits or passageways that lead to the cylinders when said device is in other than its discharge position, and when said device D is in its discharge position, as shown in Fig. 1, the openings 4 therein form portions of the air conduits or passageways that lead to the cylinders. If desired, the openings 4 in the device D may be formed by bushings 4^a so as to enable the quantity of lubricant that is supplied to each cylinder to be varied by substituting bushings having openings 4 of different diameters. I also prefer to arrange check valves 6 in the air pipes 5, as shown in Fig. 1, so as to prevent back pressure in the air conduits or

passageways into which the lubricant is admitted, when the intake valves of the engine close during the cycles of operations of the engine, thereby preventing the lubricant from being blown back out of the open ends 70 of the pipes 5^a when the device D is in its discharge position.

Normally, the device D is in such a position that it prevents air from flowing through the conduits or passageways formed 75 by the pipes 5 and 5^a; consequently, the air that is admitted to the cylinders to support combustion is taken into the cylinders through the intakes 1. As soon as the device D moves into its discharge position, 80 however, or into such a position that the openings 4 therein line up with the air pipes 5 and 5^a, the suction created in the cylinders by the movement of the pistons causes air to rush into the open ends of the 85 pipe 5^a, and thus carries the finely divided, dry lubricant in the openings 4 of the device D through the pipes 5 and into the cylinders. In other words, the air conduits or passageways formed by the coöperating 90 pipes 5 and 5^a are normally inoperative, but at certain intervals said passageways are rendered operative and a finely divided, dry lubricant is introduced into same so as to cause the currents of air that travel 95 through said passageways to carry said lubricant into the cylinders, and thus cause it to become deposited on the coöperating surfaces on the cylinders, pistons and piston rings. 100

It is immaterial how the device D that controls the admission of the lubricant is timed to operate, but I prefer to actuate said device by a mechanism which causes said device to move suddenly into and out of its discharge position and remain in its discharge position during several cycles of operations of the engine so that the lubricant holders 4^a in said device will be thoroughly cleaned out. Said mechanism is also preferably so designed that the device D will move suddenly into and out of its filling position and will remain in its filling position long enough to cause the lubricant holders 4^a in same to be filled with the lubricant that flows into same by gravity from the hopper C. One convenient way of actuating the lubricant-controlling device D and governing the time of movement of said device is shown in Figs. 2 and 3, wherein the reference character 7 designates a stub shaft on one end of the device D on which a worm wheel 8 is loosely mounted. Said worm wheel meshes with a worm 9 that is connected to a ratchet wheel 10 that is operated intermittently by a pawl 12 on a rock arm 11 actuated by a link 13 from some moving part of the engine, such, for example, as an eccentric 13^a on the crank shaft, as shown in Fig. 4. If desired, the shaft on which the 130

worm 9 is mounted could be driven continuously from some revolving shaft of the engine by means of gears, belt or in any other suitable manner. A cam 14 that is rigidly connected to the shaft 7 on the device D forms part of a mechanism for holding the device D in one or the other of its positions, and said cam is also utilized to transmit movement from the worm wheel 8 to the device D. Said cam 14 is provided on its periphery with four notches 14^a that co-operate with a roller 15^a on a spring-pressed plunger 15 that is reciprocatingly mounted in guides 17, a coiled expansion spring 16 being arranged on said plunger between one of said guides and a collar 15^b on the plunger, so as to hold the roller 15^a on the plunger pressed against the periphery of the cam 14. The worm wheel 8 is provided with a hub wheel 8^a in which a segmental-shaped slot 19 is formed, as shown in Fig. 3, and the cam 14 is provided with a laterally-projecting pin 18 that enters said slot.

When the engine is in operation the intermittent movement that is imparted to the ratchet wheel 10 causes the worm wheel 8 to turn slowly, and when the pin 18 on the cam 14 is in engagement with one end of the segmental-shaped slot 19 in the hub of the worm wheel 8, the device D will turn slowly with said worm wheel. At such times the roller 15^a on the plunger 15 rides on one of the projections on the periphery of the cam 14 that is located intermediate the notches 14^a. As soon as the roller 15^a passes over the high point of the particular projection with which it is then co-operating, the force of the spring 16 causes the plunger 15 to exert pressure on the cam 14 and thus give a sudden forward impulse to the device D, the device D remaining at rest in the position into which it has been moved until the end of the segmental-shaped slot 19 again comes in contact with the pin 18 on the cam 14. During the time the worm wheel 8 is traveling forwardly so as to catch up with the cam 14 the device D is held securely in position by the spring-pressed plunger 15 whose roller is then seated in one of the notches 14^a in said cam.

An operating mechanism of the construction above described causes the device D to remain at rest long enough to insure the lubricant holders 4^a therein to be filled with the lubricant when said device is in its filling position, and also long enough to insure said lubricant holders being completely discharged or cleaned out when the device D is in its discharging position. Furthermore, such an operating mechanism causes the lubricant to be admitted to the cylinders only at certain intervals. I wish it to be understood that my invention is not limited to the means described above for transmitting an intermittent rotary motion to the device D,

as there are many other simple ways of accomplishing the same object.

In order to prevent the lubricant in the hopper C from becoming packed or clogged in the discharge opening at the lower end of same, I have provided said hopper with an agitator 20, preferably a rotatably mounted device that is driven by means of a gear 21 thereon which meshes with a gear 22 on the device D. The dry lubricant that is introduced into the cylinders of the engine, and also any carbon that may be formed in the cylinder, is prevented from becoming mixed with the oil in the crank case by means of collecting devices arranged at the lower ends of the cylinders. In the form of my invention shown in Fig. 1 said collecting devices consist of upturned flanges or troughs 23 arranged at the lower ends of the cylinders and provided with drain pipes 24 that lead to a point outside of the crank case, said troughs being so arranged that they will receive and collect any dry lubricant or carbon that works downwardly between the pistons and the inner walls of the cylinders. The piston B of each cylinder is preferably provided at its lower end with an upturned flange or trough 25 for catching the lubricating oil that is thrown off the wrist pin bearing and preventing such oil from finding its way into the trough 23 and there mixing with the substance that is being drained out of the crank case through the drain pipe 24, the oil that collects in the trough 25 being of such a character that it can be again used for lubricating the engine. In order that the oil that collects in the trough 25 will be conducted back into the crank case, I have provided said trough 25 with a drain pipe 26 which is suspended from an extension on said trough 25 that projects inwardly a sufficient distance to cause the pipe 26 to clear the trough 23 on the cylinder, or, in other words, prevent the oil that escapes through the pipe 26 from entering the trough 23. The pipe 26 is of sufficient length to insure the lower end of same remaining below the trough 23 on the cylinder when the piston is at the upper end of its stroke, thereby preventing the oil that is escaping from the drain pipe 26 from being thrown laterally into the trough 23.

When my invention is embodied in a two-cycle internal combustion engine practically the same mechanism is employed for causing the lubricant to be carried into the cylinders, but instead of utilizing the suction in the cylinders to convey the lubricant into the cylinders, I provide means for positively forcing the lubricant into the cylinders either through the main air inlet ports or through auxiliary air inlet ports.

In the engine illustrated in Fig. 5 the reference character 27 designates a means for supplying air to the cylinders, so as to

scavenge same and 28 designates a pipe communicating with said air-supplying device and leading to the air inlet pipes 5^a of the apparatus shown in Fig. 1. During those cycles of operations of the engine that the device D is in its discharge position, as shown in Fig. 1, the air that is forced through the pipe 28 of the engine shown in Fig. 5 causes the lubricant in the openings 4 of the device D to be carried into the cylinders so as to lubricate the coöperating surfaces on the pistons and cylinders.

Having thus described my invention, what I claim, and desire to secure by Letters Patent, is:

1. A lubricating device for internal combustion engines, comprising a receptacle for holding a quantity of dry lubricant in finely divided form, a rotatable device provided with an opening for receiving lubricant from said receptacle, pipes arranged adjacent the path of movement of said device in such a manner that they will align with the opening therein when said device is in a certain position and thus form an air passageway or conduit through which air is taken into the cylinder of the engine, mechanism for rotating said device, and means for holding said device at rest when it is in its filling and discharge positions long enough to insure the proper filling and discharge of same.

2. A lubricating device for internal combustion engines, comprising a receptacle for holding a quantity of dry lubricant in finely divided form, a rotatable device that is adapted to receive lubricant from said receptacle and thereafter introduce said lubricant into a current of air that is being taken into the cylinder of the engine, an operating mechanism for said device comprising a rotatable element, a holding means for said device which causes it to remain at rest when said rotatable element is in motion, and means for transmitting movement from said rotatable element to said device, said holding means being so constructed that it imparts a quick or sudden movement to said

device when said rotatable element reaches a certain position.

3. An internal combustion engine, comprising means for introducing a dry lubricant in finely divided form into the cylinder of the engine, and means for preventing said lubricant or carbon or other abrasive matter from becoming mixed with the lubricating oil in the crank case of the engine.

4. An internal combustion engine, comprising means for introducing a dry lubricant in finely divided form into the cylinder of the engine, and means for preventing said lubricant or carbon in the cylinder from becoming mixed with the lubricating oil in the crank case of the engine, said means comprising a collecting device arranged at the lower end of the cylinder and a drain device leading from said collecting device to waste.

5. An internal combustion engine, comprising a cylinder, a piston in said cylinder, a collecting device arranged at the lower end of the cylinder for collecting any substance that works down the inner wall of the cylinder, a waste pipe leading from said collecting device, and means for preventing the oil that is thrown off the wrist pin bearing on the piston from mixing with the substance in said collecting device.

6. An internal combustion engine, comprising a cylinder, a piston in said cylinder, a collecting device arranged at the lower end of the cylinder for collecting any substance that works down the inner wall of the cylinder, a waste pipe leading from said collecting device, a collecting trough on the lower end of the piston for receiving oil that is thrown off the wrist pin bearing, and a drain pipe for conducting the oil from said trough back into the crank case.

In testimony whereof I hereunto affix my signature in the presence of two witnesses, this seventeenth day of May 1915.

GEORGE D. POGUE.
